UNITED STATES PATENT OFFICE.

WILL E. KELLER, OF LOS ANGELES, CALIFORNIA.

MOLD FORM.

Application filed September 1, 1926. Serial No. 132,959.

This invention relates more specifically to travelling concrete mold forms utilized in the erection of concrete building walls, the forms being constructed so as to render possible the attachment to the wall surfaces during the pouring operation, of tie rods, bolts, and structural beams without interfering with the movement of the forms.

In the construction of concrete buildings it is often desirable to insert and anchor at intervals during the erection of the walls metal studs projecting from the faces of the walls to facilitate the ready attachment thereto of wood beams, for the purpose of attaching wood on metal structures to the walls. Further steel beams are frequently included in concrete structures, as well as floor slab tie rods, such constructions projecting from the wall faces and interfering with the movement of the travelling mold forms. By means of the mold form construction hereinafter specifically described, steel beams, studs, tie rods, and the like may be readily placed in position and attached to the building walls at intervals during their erection without interfering with the movement or operation of the travelling forms.

In the drawings attached hereto and forming a part of this specification:

Fig. 1 is a sectional elevation of a hollow concrete wall showing the travelling form in position with stud bolts and floor tie rods embedded therein.

Fig. 2 is a side elevation of the wall and the mold form looking from the inside face of the wall.

Fig. 3 is an enlarged transverse section of the wall and mold form taken on line 3—3 of Fig. 1.

Fig. 4 is a fragmentary side elevation of the inner wall of the wall mold form illustrating the first step in inserting metal floor tie rods in the building wall.

Fig. 5 is a similar view showing the second step.

Fig. 6 is a like view showing the third step.

Fig. 7 is a like view showing the fourth step, with the form above the floor tie rods.

Fig. 8 is a like view showing the final step with the tie rod supporting plank removed from the wall.

Fig. 9 is a plan section of two oppositely disposed building walls with a steel beam connecting the walls.

Fig. 10 is a detail sectional plan taken on line 10—10 of Fig. 9.

Fig. 11 is a detail sectional elevation taken on line 11—11 of Fig. 9.

Fig. 12 is a detail perspective view of one of the ends of the beam shown in the preceding views, illustrating the form closure means for the ends of the beams.

In the construction illustrated the travelling mold forms are exactly similar in construction to the forms illustrated and described in the Waugh Patent No. 1,566,135, issued December 15, 1925, entitled Wall bonding device with the exception that they are formed of metal instead of wood, the forms operating in exactly the same manner.

Referring now specifically to the drawings the wall mold forms consist of vertical mold walls —A—B—C— and —D— arranged in pairs to form wall mold cavities. Walls —B—C— are secured together by channel irons 15, while walls —A— and —D— are secured to vertical metal beams 16 of the form structure by channel beams 17. Walks 18 for workmen are provided at the upper ends of the mold form walls, and an elevating mechanism 19 is provided, said mechanism being substantially the same as shown in the Waugh patent heretofore referred to.

As the stud bolts, wall tie rods, beams, etc. that are secured to the concrete walls and project beyond their faces as the same are poured, it becomes necessary to provide a means for supporting the same in position, and also arranging the forms in order that they may be constantly moved upwardly as the pouring of the walls progresses without interference from the projecting objects.

In the accomplishment of this object the wall —A— of the mold forms is provided with a plurality of vertically disposed slots 20 spaced the required distance apart, thus should double vertical rows of threaded studs 21 be needed for attaching wood beams to the face of the wall in the formation of interior structures, such as elevators and the like, the channel beams 17 on the outer face of the wall are cut the required length so that the adjacent ends of the beams at the slots 20 overlap the same slightly (see Fig. 3), and in order to connect the mold wall lengths together a plurality of short vertically disposed channel beams 22 are bolted to the beams 17, a pair on each side of the slots. Bolted or otherwise secured to these

last named channel beams are a plurality of horizontally disposed short channel beams, here shown as three in number and designated by numerals 23, 24 and 25. By means of the foregoing construction sufficient space in front of the slots 20 in the mold wall will be provided for the projecting ends of the threaded studs 21, and as a consequence the studs will not interfere with the upward movements of the mold forms.

Each row of the threaded stud bolts are spaced a distance apart, and in order to hold the same in position with respect to the movable forms during the wall pouring operation the same are mounted on closure boards 27, that are disposed in the slots 20 of the mold walls, the ends of the channel beams 17 bearing against the vertical edges of the boards and maintaining them in position, the boards also serving to prevent concrete from flowing through the wall slots as the walls are poured.

When it is desired to attach floor slab metal rods 30 to the building wall, the method of operating the travelling mold forms is substantially the same with the exception that the channel bars 23, 24, and 25, have to be removed and replaced at intervals during the upward movement of the forms as the rods 30 are of a greater length than the threaded stud bolts.

The method of inserting the floor slab 28 rods in position is best illustrated in the four diagrammatic views of the drawing, Figs. 4 to 8 inclusive. In Fig. 4 is illustrated the first step in securing or anchoring the metal rods 30 in the building wall. The tie rods are supported prior to the embedment of their ends in the wall by means of removable closure boards 31, 32, which are mounted in the slots 20 of the wall —A— of the mold forms, the adjacent ends of the channel beams 17 holding the same in position during the movement of the forms. Rods 30 each having hooked ends are inserted through the grouped openings 33 formed in boards 31 and arranged in the desired formation, the major portion of the rods 30 projecting beyond the outer faces of the boards 31 and their inner hooked disposed mid-way between the vertical faces of the wall. The outer ends of the tie rods may be secured against sagging prior to the embedment of their inner ends in the wall structure by wires, or other suitable securing means (not shown).

When the forms —A— reach the position as shown in Fig. 5 the uppermost channel beam 25 is removed permitting the forms to pass the rods 30. In Fig. 6 the beam 25 has been replaced and beam 24 removed, the beams being removed and replaced in order as the forms progress upwardly. When the forms reach the position shown in Fig. 6, the closure board 31, is removed from the posi-

tion shown in Fig. 5 and replaced above the board 32 as shown in Fig. 6. After the concrete of the wall has set sufficiently the boards carrying the tie rods and stud bolts may be removed in any convenient manner.

The manner of securing structural I beams 35 in position between two concrete walls 36, 37, is illustrated in Figs. 9 to 12 inclusive. In this construction the concrete mold forms —A— as well as the bracing and reinforcing 70 75 consists of timbering, bolted together in substantially the same manner as the metal constructed forms.

The inner mold walls 38 of the forms —A— are each provided with a vertical slot 39 similar in form to the slots formed in the mold walls of the metal molds, and closure boards 40, 41, are provided similar to the boards of the first forms. In this form horizontally disposed timbers 42, 43 are bolted to the outer faces of mold walls 38, their oppositely disposed ends overlapping the slots 39 for the purpose of holding the boards 40, 41, in position during the movement of the forms. Bolted to the outer faces of these timbers, are vertically disposed timbers 44, a pair on each side of the slots 39. Bolted to the outer faces of these timbers 44 are short horizontally disposed bars 45, adapted function in the same manner as the channel irons 23, 24, 25, of the first described form.

In embedding the ends of the I beam in the two walls 36, 37, the beam is suspended between the walls in the desired position by a crane (not shown) the ends of the beam extending through the vertical slots 39 in mold form walls and terminating mid-way the thickness of the walls. As the oppositely disposed ends of the closure boards 40, 41, engage the beam flanges when placed in position provision must be made to close the openings at either side of the vertical beam web to prevent the wet concrete from flowing from the mold cavities of the wall when the same are poured. To this end closures 47 are provided, each closure consisting of a pair transversely disposed wood closure plates 48 that fill the spaces between the beam flanges. Secured to the outer vertical edges of these closure plates in any suitable manner are vertically disposed flat plates 49 extending the height of the beam, and held in position by horizontally disposed bars 50 nailed thereto. Each closure is of the same width as the vertical slots 39 of the mold walls in which they are disposed, and it will be clear that they will form an effective closure around the ends of the beams and prevent concrete from flowing outwardly from the wall molds.

During the pouring of the building walls 36, 37, the closure boards are inserted in the slots 39 of the inner walls of the mold forms and move upwardly therewith. When the 125 130

upper cross bars 45 of the forms are directly underneath the beam the same are removed to permit the passage of the forms thereby, replaced after said passage, and the 5 upper closure boards 41 are then inserted in the slots. When the lower bars 45 reaches the under face of the beams the same is also removed to permit passage of the forms, and then replaced like the first bar.

10 The inner ends of the beam web at their points of embedments in the walls are provided with holes, for the passage there-through of wall reinforcing rods 51.

15 By means of the above described mold form mechanism the floor tie rods, studs, and beams of a concrete building may be easily inserted in place in the building walls without interfering with the movement of the forms.

20 What I claim is:

1. Concrete mold forms of the travelling type comprising a pair of mold walls spaced apart to form a mold cavity therebetween, said walls provided with vertically disposed 25 slots, stationary closure boards mounted in the slots adapted to carry metal attaching devices projecting at an angle from said boards, means secured to said form walls for permitting the passage of the forms past the attaching devices as the same are elevated, and means to elevate the forms.

2. Concrete mold forms of the travelling type comprising a wall mold and means to elevate the same as the concrete is poured, 30 means to support in position metal attaching devices projecting from the face of the wall prior to the pouring of the wall, and means secured to said mold form walls for permitting the passage of the forms past the attaching devices as the forms are moved upwardly.

3. Concrete mold forms of the travelling type comprising a pair of vertically disposed mold form walls spaced apart to form a mold cavity therebetween, one of the walls of said mold form walls being formed in vertical sections spaced apart, closure boards disposed between the sections, said boards adapted to carry a plurality of metal at- 45 taching members, one end of said members

disposed in the wall mold cavity for embedment therein as the wall is poured and their outer ends projecting beyond the outer face of the mold wall, and means for rigidly connecting the vertical sections of the mold 55 wall together to permit movement of the forms without interference from the attaching members.

4. Concrete mold forms of the travelling type comprising a pair of mold walls spaced apart to form a mold cavity therebetween, one of said walls being slotted vertically to form wall sections, closure members mounted between the wall sections, said members each carrying a plurality of metal members, 60 their inner ends adapted to be embedded in the wall as the same is poured and their opposite ends projecting beyond the face of the wall, and a plurality of members for connecting the adjacent ends of the wall sections together, said members being so disposed as to permit the movement of the travelling mold forms without interfering with the metal members mounted in the closure members. 65

5. Concrete mold forms of the travelling type comprising a pair of oppositely disposed wall mold forms connected together, and means secured to the oppositely disposed mold walls of said pair of forms for permitting an embedment of the ends of a horizontally disposed beam in the walls as the same are poured, said means permitting of the movement of the forms past the beam as the 70 walls are poured. 75

6. Concrete mold forms of the travelling type comprising a pair of wall mold forms connected together for vertical movement and means to move the same, and means connected to the oppositely disposed walls of said pair of forms to enable the embedment of the ends of a horizontally disposed beam in said walls as the same are poured, said means permitting a free movement of the forms past the beams as the same are elevated. 80

In witness that I claim the foregoing I have hereunto subscribed my name this 11th day of August, 1926.

WILL E. KELLER.
